[57] CLAIM

The ornamental design for an end trimmer for a cigar, as shown and described.

DESCRIPTION

FIG. 1 is a front elevational view of an end trimmer for a cigar showing my new design;

FIG. 2 is a back elevational view thereof;

FIG. 3 is a right side elevational view thereof, with the left side elevational view appearing as a mirror image of the right side view; and,

FIG. 4 is a right end elevational view thereof, with the left end elevational view appearing as a mirror image of the right end view.

The broken boundary lines form no part of the claimed design and the interior lines are shown for illustrative purposes only.
